Primary Examiner — Robin V Webster*Assistant Examiner* — James Thorn, Sr.(74) *Attorney, Agent, or Firm* — Conneely PC; Joseph Conneely(57) **CLAIM**

The ornamental design for a bra, as shown and described.

DESCRIPTION

FIG. 1 is a front view of a bra according to the design; FIG. 2 is a rear view thereof;

FIG. 3 is a left side view thereof;

FIG. 4 is a right side view thereof;

FIG. 5 is a front perspective view thereof;

FIG. 6 is a rear perspective view thereof; and,

FIG. 7 is a rear environmental view thereof.

The portions of the bra shown in broken lines in FIGS. 1-7 do not form part of the claimed design. The broken line showing of the arms, torso, and neck in FIG. 7 is for the purpose of illustrating portions of the environmental structure and forms no part of the claimed design. The bold, wavy lines shown across the straps in FIGS. 1-7 are for illustrating the boundary of the design only and do not form part of the claimed design.
